(57) **CLAIM**

The ornamental design for a trim attachment clip as shown and described.

DESCRIPTION

FIG. 1 is a top perspective view of a trim attachment clip showing our new design;

FIG. 2 is a bottom perspective view thereof;

FIG. 3 is a first side view thereof;

FIG. 4 is a top view thereof;

FIG. 5 is a bottom view thereof; and,

FIG. 6 is an end view thereof.

The broken lines in the drawings are included to show portions of the trim attachment clip that form no part of the claimed design.

The dot-dash broken lines depict the boundaries of the claimed design, and form no part thereof.
